(57) CLAIM

The ornamental design for a chair, as shown and described.

DESCRIPTION

The file of this patent contains at least one photograph executed in color. Copies of this patent with color photograph(s) will be provided by the Office upon request and payment of the necessary fee.

FIG. 1 is a front perspective view of a chair showing, in particular, the ornamental design thereof.

FIG. 2 is a front end view of the chair of FIG. 1.

FIG. 3 is a rear end view of the chair of FIG. 1.

FIG. 4 is a left side view of the chair of FIG. 1. The right side view is a mirror image of the left side view; and, FIG. 5 is a top plan view of the chair of FIG. 1.

1 Claim, 5 Drawing Sheets
(5 of 5 Drawing Sheet(s) Filed in Color)
